CLAIM

The ornamental design for a luggage wheel fork, as shown and described.

DESCRIPTION

FIG. 1 shows a front perspective view of a luggage wheel fork;

FIG. 2 shows a front elevation view of the luggage wheel fork of FIG. 1;

FIG. 3 shows a right elevation view of the luggage wheel fork of FIG. 1;

FIG. 4 shows a rear elevation view of the luggage wheel fork of FIG. 1;

FIG. 5 shows a left elevation view of the luggage wheel fork of FIG. 1;

FIG. 6 shows a top view of the luggage wheel fork of FIG. 1; and,

FIG. 7 shows a bottom view of the luggage wheel fork of FIG. 1.

The broken lines showing the luggage wheel and mounting are for the purposes of illustrating environment and form no part of the claimed design.

1 Claim, 5 Drawing Sheets(56)
